US0D1112742S

(12) **United States Design Patent** (10) **Patent No.:** **US D1,112,742 S**
(45) **Date of Patent:** **** Feb. 10, 2026**

(54) **BONE PLATE**

(71) Applicant: **Medline Industries, LP**, Northfield, IL (US)

(72) Inventor: **Ryan Niver**, Glenview, IL (US)

(73) Assignee: **Medline Industries, LP**, Northfield, IL (US)

(**) Term: **15 Years**

(21) Appl. No.: **29/853,525**

(22) Filed: **Sep. 16, 2022**

Related U.S. Application Data

(63) Continuation of application No. 29/697,643, filed on Jul. 10, 2019, now Pat. No. Des. 967,959.
